United States Patent Office

Des. 183,240
Patented July 22, 1958

183,240

CHAIR

Morton R. Cohen, Chicago, Ill.

Application February 12, 1958, Serial No. 49,611

Term of patent 14 years

(Cl. D15—1)

Fig. 1 is a perspective view of a chair, showing my new design;

Fig. 2 is a rear elevational view of the same; and

Fig. 3 is a side elevational view of the same.

I claim:

The ornamental design for a chair, substantially as shown.
